UNITED STATES PATENT OFFICE

LUTHER L. KNOX, OF PITTSBURG, PENNSYLVANIA, ASSIGNOR TO KEYSTONE FURNACE CONSTRUCTION COMPANY, OF PITTSBURG, PENNSYLVANIA, A CORPORATION OF PENNSYLVANIA.

MEANS FOR COOLING FURNACE-WALLS.

No. 919,190.

Specification of Letters Patent.

Patented April 20, 1909.

Application filed October 10, 1908. Serial No. 457,133.

To all whom it may concern:

Be it known that I, LUTHER L. KNOX, of Pittsburg, Allegheny county, Pennsylvania, have invented a new and useful Improvement in Means for Cooling Furnace-Walls, of which the following is a full, clear, and exact description, reference being had to the accompanying drawings, forming part of this specification, in which—

10 Figure 1 is a side elevation of a portion of the side wall of an open hearth furnace showing the application of my invention thereto; Fig. 2 is a section on the line II—II of Fig. 1; Figs. 3 and 4 are detail views of one of the 15 boxes or castings.

The object of my invention is to provide a 20 novel arrangement of cooling boxes or castings in the walls of the furnaces and furnace ports for the purpose of preventing the rapid destruction of the same by the cutting action 25 of the hot gases, and further to provide means for facilitating the insertion and removal of the boxes from the furnace or port wall in which they are placed.

25 The nature of my invention will be best understood by reference to the accompanying drawings, in which I have shown one form thereof applied to an open hearth furnace, and which will now be described, it 30 being premised, however, that the invention is capable of use in other classes of furnaces and that the details of construction and arrangement may be changed without departing from the spirit and scope of the invention.

35 Referring to these drawings, the numeral 2 designates the boxes or castings which, as shown, are of wedge-shape in cross-sections, being wider at their outer than at their inner 40 ends. Each box or casting is provided at one end, preferably at its low point with an inlet connection 3 for the cooling water, and at its opposite end, preferably at its highest point, with an outlet connection 4. The interior of the box may be provided with any 45 suitable arrangement of baffling 5, causing a most effective circulation of the water therethrough. To receive these boxes or castings, the furnace or port wall is provided with

50 open chambers or pockets 6 extending partially through the wall, and preferably of substantially uniform cross-section. When the boxes are placed in these chambers or pockets, spaces will be left at opposite sides 55 thereof at the inner portions of the pockets,

and these spaces are preferably filled with sand or other refractory material, as indicated at 7. In Figs. 1 and 2 I have shown a series of these boxes as placed in parallel with each other in the side wall of the furnace and extending vertically thereof, but it will be obvious that they may be arranged in various ways and may run either vertically or horizontally of the furnace, as may be desired, in any particular case.

60 By making the boxes of the peculiar cross-section described, the volume of water contained within each box may be made relatively large without unduly increasing the cooling area of their inner ends. That is to 65 say, the area of the inner ends of the boxes while sufficient to effectively check and retard the cutting action of the hot gases, is not sufficiently large to cause an undue chilling of the furnace walls and the consequent 70 chilling or lowering of the temperature of the furnace; while there is in each box a volume of water sufficient to absorb and carry off a 75 large quantity of heat.

By making the pockets or chambers of 80 uniform section, instead of to closely fit the section of the boxes, and then filling these spaces with sand or other refractory material, the construction of the furnace is simplified, since the cutting or breaking of the bricks in 85 the formation of these pockets is avoided. The provision of sand or other refractory material also provides means for compensating for the different relative expansion, and contraction, movements of the boxes or 90 castings in the wall of the furnace; and the tapered form of the boxes also facilitates their insertion and removal so that they can be readily replaced when necessary.

95 Each of the boxes is also preferably provided with one or more eyes or lugs 8 at its outer end, for the engagement therewith of a hook or other implement for removing the boxes.

As before stated, the boxes can be placed 100 either horizontally or vertically in the furnace wall, but preferably they will in all cases be so located that the cold water will enter at the lowest point of the box, and the heated water will escape at its highest point, 105 thereby providing for a most effective circulation therethrough and avoiding the formation of steam pockets. The spacing of the boxes will therefore be determined by the thickness of the port walls in which they are 110

placed, and by the diversion of the gases from the furnace.

Witnessed:

3. A regenerative reversing furnace, having its walls provided with a plurality of pockets spaced from each other by intervening brick-work of the walls, said pockets having a vertical length in excess of their width, and a cooling box seated in each of said pockets, said boxes being of diminishing cross section toward their inner ends, whereby they present relatively narrow inner vertical edges in a direction of substantially right angles to the path of the gases within the furnace, a connection for introducing a cooling fluid into the lower portion of each box, and an outlet connection from the upper portion of each box, substantially as described.
4. A furnace having a wall thereof formed with a plurality of pockets, each of the width of one or more bricks and of uniform width throughout their depth, and cooling boxes seated in the said pockets, said boxes substantially filling the outer portions of the pockets, but of diminishing cross section toward their inner ends, leaving spaces at each side thereof of increasing area toward the inner ends of the pockets, and relatively loose bodies of refractory material filling the said spaces, substantially as described.

In testimony whereof, I have hereunto set my hand.

LAWRENCE L. KNOX.
